(57) **CLAIM**

The ornamental design for a billiard ball, as shown and described.

DESCRIPTION

FIG. 1 is a perspective view of a billiard ball showing my new design;

FIG. 2 is another perspective view thereof;

FIG. 3 is a front elevational view thereof, the rear elevational view is identical;

FIG. 4 is a left elevational view thereof, the right side view is identical; and,

FIG. 5 is a top side view thereof the bottom plan view is identical.

The broken lines in the figures are for the purposes of illustrating portions of the billiard ball, which form no part of the claimed design.
